UNITED STATES PATENT OFFICE.

WILLIAM A. J. LOWE AND JOSEPH H. LONG, OF KINGSPORT, TENNESSEE, ASSIGNEES TO
UNIVERSAL FRUIT STAND COMPANY, OF JOHNSON CITY, TENNESSEE, A CORPOR-
ATION OF TENNESSEE.

DISPLAY-STAND.

1,326,755.

Specification of Letters Patent. Patented Dec. 30, 1919.

Application filed June 9, 1919. Serial No. 302,824.

To all whom it may concern:

Be it known that we, WILLIAM A. J. LOWE and JOSEPH H. LONG, citizens of the United States, residing at Kingsport, in the county 5 of Sullivan and State of Tennessee, have invented new and useful Improvements in Display-Stands, of which the following is a specification.

This invention relates to improvements 10 in display stands, more particularly designed for the display of fruit.

One of the principal objects of the invention is to provide a wheeled stand having a receptacle for receiving the fruit and an 15 upright member carried by the stand and provided with means for suspending bunched fruit, such as bananas.

Another object of the invention is to provide a simple and effective arrangement of 20 parts whereby the structure is held in assembled position with the use of but a few bolts,

Still another object of the invention is to provide hoisting means for lifting the 25 bunches of fruit to the suspending means on the upright.

The invention also consists in certain other features of construction and in the combination and arrangement of the several parts, to be hereinafter fully described, 30 illustrated in the accompanying drawings and specifically pointed out in the appended claims.

In describing our invention in detail, reference will be had to the accompanying drawings wherein like characters denote like or corresponding parts throughout the several views, in which:—

Figure 1 is a perspective view of the invention;

Fig. 2 is an enlarged view, partly in section, of the upper part of the device;

Fig. 3 is a section on line 3—3 of Fig. 2;

Fig. 4 is a section on line 4—4 of Fig. 1;

Fig. 5 is a sectional detailed view of one corner of the stand.

In these views 1 indicates a tubular member which has its lower end provided with a coupling 2 which carries four coupling 50 arms 3. These arms receive the inner ends of the horizontally-extending tubular members 4 which have their outer ends curved downwardly as at 5. These ends rest upon a rectangular frame 6 formed of a metal 55 strip with its corners bent to provide flat

portions upon which the ends of the members 4 rest. These flat portions are provided with holes through which the shanks of the casters 7 pass into the ends of the members 4. In this way the frame 6 is connected with the ends of the members 4. 60

A box-like receptacle 7 rests upon the horizontal members and the bottom of this receptacle is provided with an opening through which the tubular member 1 passes. 65 The upper end of the tubular member 1 is provided with a coupling, 8 upon which rests the top 9 and said top is also supported by the four legs 10. Each of these legs has its upper end suitably connected with 70 the top and its lower end bent at right angles to provide a horizontal portion 11 which rests upon the bottom of the receptacle and then the strip forming the leg is bent upwardly at an incline as at 12 and 75 bolted to the tubular member 1. Bolts 13 pass through the horizontal parts 11 and the bottom of the receptacle into the horizontal members 4.

The tubular upright member 14 has its 80 lower end passing through an opening in the top 9 and engages the coupling 8 and the upper end of this upright carries a ball bearing ring 15 which forms a ball brace for the balls 16. A cap member 17 fits over 85 the upper end of the upright and rests upon the balls. This cap member is provided with a downwardly extending socket 18 which is centrally arranged and projects into the upright. This cap member has 90 formed on its side walls three bosses 19 which are each provided with a socket 20, all of the sockets being open at the upper end of the cap. The side sockets are adapted to receive the bowed members 21, which are pref- 95

erably formed of tubing, and these bowed members are provided with the caps 22 which are screw-threaded to their free ends and these caps carry the hooks 22'. The central socket 18 receives the hoisting standard 23 which has its upper end bent at right angles and the two arms of which are connected together by the brace 24. This standard is adapted to receive the pulley 25 for the hoisting cable. The bowed members 21 are connected together by the triangular-shaped brace plate 26 which is bolted to the said members. 100

It will thus be seen that the stand may be easily moved from one place to another 110

by reason of its wheeled base and when the receptacle 7 is filled with fruit or other articles the weight will prevent the device from being tilted over by the weight of the 5 bunches of bananas suspended from the hooks 22' or while they are being hoisted into position. As the cap member is rotatably supported, the bunches of bananas may be moved to a position where the bananas may be easily removed from the stems. 10 The top 9 will prevent anything from dropping off the bunches of bananas into the receptacle and also acts as a table when desired.

15 What we claim is:—

1. A device of the class described comprising a stand, an upright member carried thereby, a cap member rotatably mounted on the upper end of the upright member, 20 said cap member having vertically disposed sockets therein, one of which is located in the center and the others in the sides, bowed members having the shanks engaging the side sockets, hooks carried by the outer ends

of said members and a hoisting standard 25 mounted in the central socket.

2. A device of the class described comprising a stand consisting of a central tubular member, horizontal members connected with the lower end thereof and having their outer ends curved downwardly, a rectangular frame engaging said ends, casters having their shanks passing through the frame into said ends, a receptacle mounted on said horizontal members and having a hole therein through which the tubular member passes, a top resting upon the tubular member, legs connected with the top and extending into the receptacle and having upwardly inclined portions having their ends secured to the tubular member, and bolts connecting the said legs to the bottom of the receptacle and to the horizontal members. 35 40

In testimony whereof we affix our signatures.

WILLIAM A. J. LOWE.
JOSEPH H. LONG.
